UNITED STATES PATENT OFFICE.

HERVEY SMITH, OF ERIE, PENNSYLVANIA.

CONVEYER APPARATUS.

SPECIFICATION forming part of Letters Patent No. 333,352, dated December 29, 1885.

Application filed October 5, 1885. Serial No. 179,050. (No model.)

To all whom it may concern.

Be it known that I, HERVEY SMITH, a citizen of the United States, residing at Erie, in the county of Erie and State of Pennsylvania, have invented certain new and useful Improvements in Conveyer Apparatus; and I do hereby declare the following to be a full, clear, and exact description of the invention, such as will enable others skilled in the art to which it applies to make and use the same.

This invention relates to carrier systems for store and other service; and it consists in certain improvements in the construction thereof, which will be hereinafter fully described, and pointed out in the claims.

My invention is illustrated in the accompanying drawings, as follows: Figure 1 is a perspective view of a switch on a conveyer-track. Fig. 2 is a plan view of the under side of the switch. Fig. 3 is a plan view of the top side of the switch, showing the parts in position for the passage of cars on the main line. Fig. 4 is a like view to Fig. 3, but shows the parts in position to divert a car onto the switch. Fig. 5 is a side elevation of the switch. Fig. 6 is a longitudinal vertical section of the switch. Fig. 7 is an end view of the switch from the right of Fig. 1, and shows a car passing the switch. Fig. 8 is a top view of the switch and car, and shows the car being diverted to the switch-track. Fig. 9 is a top view of the switch, showing the parts A, A' separated, and illustrates the method of attaching the switch to a wire track. Fig. 10 (which is on Sheet 2) shows a section of double-faced track made of wood or iron.

It will be seen from the drawings that my improved switch is adapted to that class of conveyers in which the car consists of a trolley which runs on the track, and is provided with a stem or pendant which extends below the track and supports the object to be carried. It will also be seen that the car shown is substantially like the one shown in Letters Patent No. 326,928, granted to my assignee on September 22, 1885, which is provided with two sets of wheels, one running on the track and the other embracing the under side of the track, and by observing Fig. 2 it will be seen that the switch is adapted for that kind of a car; but it must not be inferred from this that my improvements are limited to that kind of a car,

for they may be used in connection with almost every form of car devised.

My improvements may also be applied to various forms of track; but I have only shown them applied to single-rail tracks, and I have illustrated the manner of applying them to a taut-wire track. This feature of my invention consists in making the switch in two parts, A and A', and clamping them upon the wire B, forming the track by bolts a, &c. Figs. 5, 6, and 9 show this feature very clearly. Figs. 5 and 6 show how the switch-irons may be made crowning, so as to clamp the straight wire B without bending it and get space above the wire for the adjustment of the parts forming the switch proper, and in Fig. 1 it is shown by dotted lines how the wire may be deflected down and up again within the two parts A A'. 70

If the track is made as shown in Fig. 10, the switch-irons will not be clamped upon it, but it will be enlarged, as shown, at the switch-points to receive the parts of the switch, and if the track is made of a plain bar set edgewise 75 the side extensions or ledges, A² A³, will be bolted to it.

The ledges A² and A³, just named, are an important feature of the invention. They are so placed on the side of the track that the wheels 80 of a passing car will rest with their flanges on these ledges, (see Fig. 7,) and if the car has a lower set of wheels the flanges of these wheels will operate on the under side of the ledges. This gives the car while passing a switch such 85 a bearing on the track as will prevent it from swinging or swaying. The ledges A² A³ also form a seat for the switch-tongues E E' E² and the slide-bars F F', by which the tongues are moved. These tongues are pivoted on pins e 90 e' e', and the slide-bars F F' lie in grooves f f transverse the track in the face of the ledges. (See Fig. 9.) The slide-bars F F' are shown in Figs. 1, 3, and 4 as connected together by a lever, G, which is pivoted at g between them, 95 so that the two bars will move at the same time, but in opposite directions. The bar F is connected with the tongues E and E', and the bar F' with the tongue E², and therefore the two tongues E and E' will move together in the 100 same manner, and the tongue E² will move at the same time but in an opposite manner. The changed positions of the tongues and the effect of such changes is clearly shown in Figs. 3 and 4.

The movement of the switch-tongues is effected by a fender, *h*, on the car coming in contact with the post *H*, which is on the bar *F* on the lever *G*, and the parts are reacted by the 5 spring *i*.

- In Fig. 8 a modified construction is shown. Here the tongue *E*² is not connected with the lever *G*, but with another lever, *G'*, which is reacted by a spring, *i'*, and it is so adjusted that o the tongue *E*² is kept in place across the space *c* between the track *C* and the ledge *A*³ all the time, but can be pushed aside by stem *K* of a passing car. In this construction the movement of the tongue *E*² is like that of a spring- 5 latch, and is entirely independent of the movement of the two tongues *E* and *E'*, which must move together and be moved by the passing car. The fender *h* on the car extends some distance ahead and behind the trolley-wheels, and o extends far enough to one side to come in contact with the post *H*. The posts at the several switches on the line will be of different heights, and the fenders on the several cars will be placed in different positions vertically, and 5 thus only cars which are destined for a particular switch will come in contact with the post *H* at that switch, and all other cars will pass without affecting the switching devices at that station. When the fender does come in contact o with the post *H*, it is so far extended in front of the wheels that it effects a movement of the tongues before the wheels reach them. The rear extension of the fender is for holding the tongues in place until the trolley gets onto the 5 side track, *C*, and the extension *H'* on the post *H* is to enable this to be done with a less rear extension of the fender *h* than would otherwise be required. When the tongue *E*² is made to operate as in Fig. 8, the rear extension of the o fender *h* may be very slight. Where the car has a lower set of wheels, as shown, there is no necessity of movable tongues on the underside of the switch-ledges. Fig. 2 shows how the track should be cut below the switch.

- 5 It has been referred to above that when the track is made of a taut wire the switch-irons *A* and *A'* will be clamped upon the wire, and that the wire will either be deflected down in its passage through the switch-irons, as shown by o dotted lines in Fig. 1; or the switch-iron will be made crowning, as in Figs. 5 and 6, so the wire will be far enough below the surface to allow the switch-tongues to be placed above it. It will be seen that this obviates the necessity 5 of cutting the wire at the point where the wheel-flanges pass over it when the car runs off onto the switch-track.

The section of track shown in Fig. 10 is intended to be made of wood; but of course it o may be made of iron. Its distinguishing feature is that the tread of the track is in the wings *a*². The central rib, *a'*, is simply to guide the wheels. This rib lies in between the flanges of the wheels, and the wheels do not tread on it but on the faces at the side of the rib, so the wheels tread on the edges of their flanges in place of on the space between the flanges. The bene-

ficial result of this construction is that the car will run with much less friction of the track on the flanges than where the tread is between the flanges. If the track is to be used with a car having the lower set of wheels, a rib, *a'*, should be on the under side of the rail, also as shown. Otherwise it is not essential.

In Fig. 4 the switch-track *C* is represented 75 as made of the form shown in Fig. 10. The ledges *A*² and *A'* at the switches being, as before stated, so placed as to receive the tread of the wheel-flanges, as seen in Fig. 7, give the same effect as the faces *a*² of the track seen in 80 Fig. 10.

In a companion application I show certain of the features of construction I here show, together with others, and I there make a generic claim to said features.

85

What I claim as new is—

1. In a carrier apparatus, substantially as shown, the combination, with a car having a trolley which embraces three sides of the track and operates on the upper and lower faces 90 thereof, of a track having a central rib and ledges or extensions on each side of said rib to receive the tread of the flanges of the trolley-wheels, for the purposes mentioned.

2. In a carrier apparatus, substantially as 95 shown, the combination, with a car having two sets of double-flanged wheels arranged to operate on both the upper and lower faces of the track, of a track having a central rib and ledges or extensions on each side of said rib to receive the tread of the flanges of the trolley-wheels, for the purposes mentioned.

3. In a carrier apparatus, substantially as shown, the combination, with a branch or switch track and a main track, of ledges or 105 projections on either side of the main track opposite the end of the switch-track, on which ledges are adjusted the means for diverting the car from one of said tracks to the other.

4. In a carrier apparatus, substantially as 110 shown, the combination, with a branch or switch track and a main track, which consists of a taut wire, of ledges or projections which are clamped upon the main track opposite the end of the switch-track, and are made crowning, so as to extend above the main track, and are provided upon their upper surface with a proper formation to serve as a track for the car above the embraced wire, and also with means for diverting the car from one of said tracks to 115 the other.

5. In a carrier apparatus, substantially as shown, the combination, with a branch or switch track and a main track, which consists of a taut wire, of ledges or projections which 125 are clamped upon the main track opposite the end of the switch-track and support the devices by which the car is diverted from one of said tracks to the other.

6. In a carrier apparatus, substantially as 130 described, the combination, with a branch or switch track and a main track, which consists of a taut wire, of ledges or projections which are clamped upon the main track opposite the

end of the switch-track, and are provided on their upper surface with a proper formation to serve as a track for the car above the embraced wire track, and also with means for diverting the car from one track to the other.

5. 7. In a carrier apparatus, substantially as shown, the combination of a switch-track and a main track, a ledge or projection on the main track opposite the end of the switch-track, a space, *c*, between the end of the switch-track and the said ledge, and a pivoted tongue on the said ledge, which swings over and opens the said space *c*.

8. In a carrier apparatus, substantially as shown, the combination of a switch-track and a main track, a ledge or projection, and the main track opposite the end of the switch-track, a space, *c*, between the end of the switch-track and the said ledge, and a pivoted tongue on the 15 said ledge, which swings over and spans the said space *c*.

9. In a carrier apparatus, substantially as shown, the combination of a switch-track and a main track, a ledge or projection on the main track opposite the end of the switch-track, a space, *c*, between the end of the switch-track and the said ledge, a pivoted switch-tongue on the said ledge, which swings over and spans the space *c*, and two other pivoted switch-tongues 25 on said ledge, which lie parallel and are moved simultaneously and operate to keep the car on the main track or diverted therefrom, substantially as set forth.

10. In a carrier apparatus, substantially as shown, the combination, with the main and the switch track, of the two parallel pivoted switch-tongues *E E'*, the sliding bar *F*, connecting said tongues, and means, substantially as shown, for moving said bar from the passing car.

11. In a carrier apparatus, substantially as shown, the combination, with the main and the switch track, of the two parallel switch-tongues *E E'*, the sliding bar *F*, connecting said tongues, the tongue *E'*, the bar *F'*, for moving said tongue *E'*, and the lever *G*, connecting said bars *F* 40 and *F'*, and pivoted between them, so as to move them in opposite directions, and means, substantially as shown, for moving said lever *G* from the passing car.

12. In a carrier apparatus, substantially as shown, the combination, with the main and the switch tracks, of the parallel switch-tongues *E E'*, arranged with relation to said tracks, as shown, the sliding bar *F*, for moving said tongues simultaneously, the post *H*, connected with said sliding bar, and the fender *h* on the car for operating upon said post.

In testimony whereof I affix my signature in presence of two witnesses.

HERVEY SMITH.
